WINDOW DECAL

Thomas W. Hotchkiss, 3% Delta Design Associates, 310-B
Boston Post Road, Milford, Conn. 06460

Filed Sept. 30, 1974, Ser. No. 510,734

Term of patent 14 years

Int. Cl. D19—08

U.S. Cl. D59—2 A

Fig. 3

Fig. 1

Fig. 4

Fig. 2

Fig. 5

Fig. 6

FIG. 1 is a front elevational view of a window decal embodying my new design;

FIG. 2 is a rear elevational view in an inverted position of the window decal of FIG. 1;

FIG. 3 is a left end elevation thereof;

FIG. 4 is a right end elevation thereof;

FIG. 5 is a bottom edge view thereof; and

FIG. 6 is a top edge view thereof.

I claim:

The ornamental design for a window decal, as shown and described.
